UNITED STATES PATENT OFFICE.

EDWIN E. FREDERICK, OF AVALON, PENNSYLVANIA, ASSIGNOR OF ONE-FOURTH TO FRANK B. ELDER, OF BELLEVUE, PENNSYLVANIA.

GAS-REGULATING MEANS.

SPECIFICATION forming part of Letters Patent No. 733,954, dated July 21, 1903.

Application filed April 9, 1903. Serial No. 151,890. (No model.)

To all whom it may concern:

Be it known that I, EDWIN E. FREDERICK, a citizen of the United States, residing at Avalon, in the county of Allegheny and State of Pennsylvania, have invented a new and useful Gas-Regulating Means, of which the following is a specification.

This invention relates more particularly to means for regulating the flow of gas to incandescent burners, though it may be employed for other analogous purposes. In order to operate incandescent burners most successfully, the flow of gas must be controlled at the extreme point of exit, so that the force of discharge will not be seriously interfered with.

In view of the fact that gas varies in pressure it is desirable to vary the discharge-orifice to suit such differences. The original manner of accomplishing this was to ream the opening; but if it was the least bit too large or too small the candle-power was reduced. Various devices have lately been employed for changing the size of the discharge-orifices; but those which to my knowledge have proven practicable and have been placed generally on the market either require the services of an expert to operate them or else are comparatively expensive to manufacture.

It is the object in the present invention to provide an extremely-simple device for regulating the pressure, which device can be cheaply manufactured and readily and properly operated by any one of ordinary intelligence.

The device, furthermore, because of its quick-action qualities is useful for turning down the light without extinguishing it entirely, thereby acting in the nature of a bypass.

The preferred means for accomplishing these objects is illustrated in the accompanying drawings, wherein—

Figure 1 is a side elevation of the invention, the parts being shown on an enlarged scale in order to more clearly illustrate them. Fig. 2 is longitudinal sectional view through the same. Fig. 3 is a cross-sectional view. Fig. 4 is a detail perspective view of the valve, and Fig. 5 is a view in elevation of the holding-cap.

Similar reference-numerals indicate corresponding parts in all the figures of the drawings.

In the embodiment herewith illustrated a suitable conduit or body 10 is employed, having a passage-way 11 therethrough. The lower end of the conduit is counterbored and internally threaded, as shown at 12, to permit its attachment to a gas-bracket in the ordinary manner. The upper end of the conduit is formed into a nipple 13, the passage-way therefrom being contracted, as shown at 14, and constituting a valve-seat.

A valve is slidably mounted in the passage-way and comprises a head 15, carrying a needle 16, which is movable into the discharge-orifice. The head is preferably angular in cross-section, and a socket 17 extends into the same from one face, the inner end of the socket being rounded and the outer portion thereof being outwardly flared, as shown in Figs. 2 and 3. The wall of the conduit is provided with an opening 18 therethrough that alines with the socket 17, and the outer portion of this opening is enlarged and rounded to form a socket. An actuating-lever 19 is also employed in the structure, said lever extending through the opening 18 and having an intermediate enlarged ball 20, that fits in the socket portion of said opening. The inner end of this lever is also provided with a ball enlargement 21, which fits on the socket 17 of the valve. The lever is held in place by a cap-plate 22, having a bifurcation 23 and a circular recess 24, in which the outer portion of the intermediate ball 20 of the lever fits. The cap-plate is held in place by a fastening-screw 25, that engages the conduit and serves to clamp said plate against the ball 20, so as to constitute friction holding means for the lever and urge the ball 20 thereof into close engagement with the walls of the socket in order to prevent the escape of gas.

The operation of this regulator will be apparent. When the handle end of the lever is raised, the needle will be correspondingly lowered, and the discharge-orifice may thus be opened to any degree desired. The plate 22 serves as a frictional holding device, so that the valve will remain in any position.

This plate furthermore serves to hold the intermediate ball against the wall of the opening, thereby forming a gas-proof joint. The connection between the valve and the lever 5 is also very simple and at the same time permits the free movement of the parts. Should it become desirable to remove the valve, the inner end of the lever may be readily withdrawn through the opening, as the inner ball 10 is smaller than the same. It will be apparent that the structure can be manufactured at very small cost, and the parts are not liable to become deranged. The valve can be operated, if desired, for turning down the light, 15 and the needle may be constructed so as to afford a small passage-way for the gas when it is in closed position, thus acting as a by-pass.

From the foregoing it is thought that the construction, operation, and many advantages 20 of the herein-described invention will be apparent to those skilled in the art without further description, and it will be understood that various changes in the size, shape, proportion, and minor details of construction 25 may be resorted to without departing from the spirit or sacrificing any of the advantages of the invention.

Having thus described my invention, what I claim as new, and desire to secure by Letters 30 Patent, is—

1. In gas-regulating means, the combination with a conduit having a valve-seat therein, of a valve movable toward and from the seat, and an actuating-lever fulcrumed in 35 one wall of the conduit and having a connection with the valve for moving the same.

2. In gas-regulating means, the combination with a conduit having a valve-seat therein, of a valve movable toward and from the 40 seat, and an actuating-lever mounted on the conduit and having a movable engagement at its inner end with the valve.

3. In gas-regulating means, the combination with a conduit having a socket in its 45 wall and a valve-seat, of a valve coacting with the seat, and a lever having a ball that fits in the socket, said lever also having a connection with the valve.

4. In gas-regulating means, the combination 50 with a conduit having an opening therethrough, the outer portion of the opening being enlarged to form a socket, of a valve-seat located in the conduit, a valve coacting with the seat, and a lever passing through the conduit-opening and having an intermediate enlargement located in the socket, the inner

portion of said lever being connected to the valve.

5. In gas-regulating means, the combination with a conduit having an opening therethrough, the outer portion of the opening being enlarged to form a socket, of a valve-seat arranged within the conduit, a valve coacting with the seat, a lever passing through the conduit-opening and having an intermediate 65 ball enlargement fitted in the socket, the inner portion of said lever being connected with the valve, and a cap fitted over the ball and secured to the conduit.

6. In gas-regulating means, the combination with a conduit having a valve-seat, of a valve coacting with the seat and provided with a socket, and an actuating-lever having its inner end movably engaged in the socket. 70

7. In gas-regulating means, the combination with a conduit having a valve-seat, of a valve coacting with the seat and provided with a socket, and an actuating-lever having a ball at its inner end that movably fits in the socket. 75

8. In gas-regulating means, the combination with a conduit having a nipple and a valve-seat located therein, said conduit being provided with an opening therethrough the outer portion of which is enlarged to form 80 a socket, of a valve slidably mounted in the socket and movable toward and from the seat, and a lever having a ball enlargement on its end and on an intermediate portion, the end enlargement fitting in the socket of the valve, 85 and the intermediate enlargement being located in the socket of the conduit.

9. In gas-regulating means, the combination with a conduit having a valve-seat, of a valve coacting with the seat, a lever movably 95 mounted on the conduit and arranged to actuate the valve, and holding means for the lever frictionally engaging the same.

10. In gas-regulating means, the combination with a conduit having a valve-seat and 100 a socket, of a valve coacting with the seat, an actuating-lever for moving the valve, said lever having an enlargement fulcrumed in the socket, and means for holding the enlargement in the socket. 105

In testimony that I claim the foregoing as my own I have hereto affixed my signature in the presence of two witnesses.

EDWIN E. FREDERICK.
